UNITED STATES PATENT OFFICE.

FELIX STERNTHAL, OF CHICAGO, ILLINOIS.

SILVERWARE CONTAINER.

Application filed May 25, 1926. Serial No. 111,552.

My invention relates to a silverware container and the same has for its main object to provide an article of this character which will embody certain desired features of simplicity, efficiency and convenience, and which will be economical in manufacture.

Another object of my invention is to provide a silverware container capable of being folded up into a neat, attractive and compact form and capable also when spread out, of effectively displaying the articles of silverware arranged therein.

Other objects will appear hereinafter.

The invention consists in the combinations and arrangements of parts hereinafter described and claimed.

The invention will be best understood by reference to the accompanying drawings forming a part of this specification, and in which,

Fig. 1 represents a plan view of my improved container, this view showing the inner side of the same with the partition partly broken away;

Fig. 2 represents an exterior view of the container as it appears when folded;

Fig. 3 represents an enlarged transverse sectional view taken on the line 3—3 of Fig. 1;

Fig. 4 represents another plan view of the container, showing the outer side thereof;

Fig. 5 is an enlarged detail section taken on the line 5—5 of Fig. 1 but showing the knife in full lines;

Fig. 6 is a detail sectional view taken on the line 6—6 of Fig. 1; and,

Fig. 7 is a similar view taken on the line 7—7 of Fig. 1.

The preferred embodiment of my invention, as illustrated in the accompanying drawings, comprises an outer sheet 8 and an inner sheet 9, the same being coextensive and being bound at their marginal edges by a binding strip 10 which is secured thereto

by a suitable line of stitching 11. The sheet 8 comprises essentially a backing sheet and may be made of any pliable material suitable for the purpose, while the inner sheet 9 comprises a wrapping sheet and is made preferably of flannel or other suitable pliable material customarily employed for wrapping silverware.

The container of my present invention is intended to hold a large number of articles of silverware and to be capable of being folded into a neat, attractive and compact

form. With this end in view, the connected outer and inner sheets 8 and 9 are designed to be folded longitudinally upon a medial folding line 12 so as to provide a book-fold comprising right and left-hand sections 13 and 14. Arranged upon the inner sheet 9 of each section are two opposing carrier strips 15 and 16. Each strip 15 is secured along the free edge of its section upon the inner sheet 9, while each strip 16 is located upon the inner sheet 9 at a suitable point between the strip 15 and the folding line 12. Each of the strips 15 is seamed all around its marginal edge upon the inner sheet 9; part of the marginal edge being secured by stitching 17 directly to the inner sheet 9 while the remainder of the marginal edge, with matches with the free edge of the section, is stitched with the binding strip 10. Each of the strips 16 has its edge 18, which confronts the strip 15, free and unattached, while the remainder of its marginal edge is secured directly to the inner sheet 9 by stitching 19 except at the free edge of the section where, as in the previous instance, it is secured with the binding strip 10. The carrier strips 15 and 16, thus arranged upon each section, are provided lengthwise thereof with corresponding series of eyes 20 adapted to receive the articles of silverware; it being observed from Fig. 1 that the eyes in the strip 15 are located closely adjacent the edge confronting the other strip 16, while the eyes in the strip 16 are located a distance from the free edge 18 which confronts the strip 15. By this arrangement, an article of silverware as 21 is applied by passing it through an eye of the strip 16 and then through an aligned eye of the strip 15 so that the article is secured transversely of the section with its handle portion coming adjacent the folding line 12. It will be evident that a row of articles may thus be secured in the carrier strips 15 and 16 arranged upon the wrapping sheet 9 of each section; and from an inspection of Fig. 1 it will be seen that, owing to the arrangement of the carrier strips and of the eyes therein, the articles of silverware while being securely retained are nevertheless displayed to such an extent that an observer may note the style and design thereof without removing them from the carrier strips.

The inner and outer sheets at the end of one section, herein shown to be section 13, are formed with flap extensions 22 which are

secured at their marginal edges by a continuation 23 of the binding strip 10. These connected flap extensions 22 are designed to be folded over onto the outer sheet 8 when the 5 folded over sections have together been folded upon themselves into compact form as illustrated in Fig. 2. Attached to the flap extensions 22 are two tying tapes 24 and 25 which are adapted to be passed around the 10 folded container for securing it in folded condition. Instead of folding the folded over sections in the manner illustrated in Fig. 2, it will be obvious that the folded over sections may be rolled up and secured in cylindrical form by means of the tying tapes 24 and 25. A sheet 26 of pliable material is attached at one edge along the folding line 12 and serves as a partition between the articles of silverware carried by the sections. 15

20 While I have illustrated and described the preferred form of construction for carrying my invention into effect, this is capable of variation and modification without departing from the spirit of the invention. I, 25 therefore, do not wish to be limited to the precise details of construction set forth, but desire to avail myself of such variations and modifications as come within the scope of the appended claims.

30 Having described my invention what I claim as new and desire to secure by Letters Patent is:

1. A silverware container including pliable sheet means; two pliable strips extending across the sheet means in opposing relation and seamed to the sheet means along their outer longitudinal edges; said strips being provided with corresponding series of 35 eyes alined and cooperating to receive and retain articles of silverware, passed first through the eyes of one strip and then through the corresponding eyes of the other 40

strip; one of said strips being open at its confronting edge to provide free passages from the eyes therein; and the other of said strips being seamed along its confronting edge to compel passage to the eyes therein from the top surface thereof, substantially as described. 45

2. A silverware container including outer and inner pliable sheets sewed together and affording right and left-hand sections doubled together along a folding line; a pair of pliable strips extending across and secured to the inner sheet of each section and 50 provided with corresponding series of eyes alined and cooperating to receive and retain articles of silverware; passed first through the eyes of one strip and then through the corresponding eyes of the other strip, substantially as described. 55

3. A silverware container including outer and inner pliable sheets sewed together and affording right and left-hand sections doubled together along a folding line; a pair of pliable strips extending across and secured to the inner sheet of each section and 55 provided with corresponding series of eyes to receive articles of silverware; connected extensions on the outer and inner sheets of one 70 section; and means associated with said extensions for fastening the container in folded condition, substantially as described.

4. A silverware container comprising a pliable cover member, one or more pliable 75 flaps attached thereto, a pliable strip attached thereto along both longitudinal edges, a corresponding series of eyelets in each of said flaps and in said strip aligned so as to receive and retain articles of silverware thrust therethrough, substantially as described. 80

In testimony whereof I have signed my name to this specification.

FELIX STERNTHAL.
